UNITED STATES PATENT OFFICE

FRANK X. MUENZER, OF ELMORE, OHIO, ASSIGNOR TO THE MULTIPLEX CONCRETE MACHINERY COMPANY, OF ELMORE, OHIO, A CORPORATION OF OHIO

BUILDING BLOCK

Application filed February 28, 1929. Serial No. 343,287.

This invention relates to a building block of concrete or similar material, with special reference to its use in the construction of chimneys.

5 The general object of the invention is to provide a block of this kind having novel and improved features which facilitate the setting of the blocks, which hold the flue lining in correct position, and which serve efficiently 10 as a heat insulator.

These various features, in their preferred embodiment, and the advantages resulting therefrom, will be more particularly explained in connection with the accompanying 15 drawings, in which

Figure 1 is a plan view of a block made according to the invention.

Figure 2 is a side elevation of the same with a portion broken away on the line 2—2 of 20 Figure 1.

Figure 3 is an isometric view illustrating the adaptation of the invention to chimney construction.

As illustrated in the drawings, the block 5 is in the form of a hollow square, although its precise shape is not material to the invention. The walls of the block are formed on their inner faces with vertically disposed ribs 6, within which the flue lining 7 has a 10 close fit. The walls of the block are formed with a series of air pockets 8 which extend from its bottom face nearly to the top of the block. These pockets serve as a non-conductor of heat from the flue to the outside of 15 the wall. In making the block these pockets are formed by cores secured to the support on which the pallet rests and the pockets are 20 preferably tapered to facilitate the withdrawal of the cores when the block is lifted 25 from the mold.

The upper face of the block is formed with a channel 9 which preferably extends continuously about the block near its outer edge and the bottom face of the block is 45 formed with a ridge 10 adapted to mate with the channel in a similar block disposed therebeneath.

In laying the blocks one above the other, the cement or mortar may be spread in the channel 50 9 and the next block laid thereon without

any of the cement or mortar working into the air spaces. The ribs 6 serve as accurate guides to retain the flue lining in position and may be easily chipped off in case a section of the flue lining is slightly oversized, while the 55 spaces between the ribs serve as additional air spaces to prevent conduction of heat to the outer surface of the chimney.

Half blocks, as shown at 11, may be made by inserting a partition plate across the center of the mold. These half blocks may be laid adjacent the main chimney to provide for a smaller auxiliary flue 12, and when so laid, may be bonded to the main chimney by angular metallic strips as indicated at 13, or 60 the two flues may be bonded together by courses of brick laid alternately with the 65 blocks.

Provision may be made for inlets into either of the flues as indicated at 14 by inserting cores in the molds, so that each of the 70 adjacent blocks provides half of the opening.

It will be understood that these blocks can be made in the usual concrete block machine 75 by providing the necessary cores for the same.

While I have shown and described in considerable detail the preferred form of the block, it is apparent that the various features thereof may be considerably modified 80 without departing materially from the scope of the invention as claimed.

What I claim is:

1. A chimney block having side walls 85 formed with internal vertical ribs constituting guides adapted to fit against the flue lining, leaving continuous vertical air spaces at the sides of each rib, a channel in the upper face of each side wall, a ridge on the 90 lower face of each side wall and adapted to mate with the corresponding channel in a similar block disposed therebeneath, and tapered air pockets extending upwardly from the bottom surface of the block in the planes 95 of the ridges and terminating below the upper surface of the block.

2. A chimney block having a channel extending about its upper face between the inner and outer edges thereof, a ridge on the 100

lower face of the block adapted to mate with the corresponding channel in the upper face of a similar block disposed therebeneath, and tapered air pockets extending upwardly from the bottom surface of the block in the planes of the ridges and terminating below the upper surface of the block.

In testimony whereof I have hereunto signed my name to this specification.

16
